UNITED STATES PATENT OFFICE.

DENNIS S. BLUE AND LEANDER HALTER, OF FREMONT, OHIO.

CULTIVATOR.

SPECIFICATION forming part of Letters Patent No. 356,094, dated January 18, 1867.

Application filed November 9, 1866. Serial No. 218,390. (No model.)

To all whom it may concern:

Be it known that we, DENNIS S. BLUE and LEANDER HALTER, citizens of the United States, residing at Fremont, in the county of 5 Sandusky and State of Ohio, have invented certain new and useful Improvements in Cultivators; and we do hereby that the following is a full, clear, and exact description of the same, reference being had to the annexed 10 drawings, making a part of this specification, and to the letters and figures of reference marked thereon.

Figure 1 of the drawings is a perspective view of our improved cultivator; Fig. 2, a top 15 plan view partly in section; Fig. 3, a detail sectional view taken on line *x* *x* of Fig. 2; Fig. 4, a similar view taken on line *y* *y*, and Fig. 5 a detail sectional view through the seat and seat-support.

20 The present invention has for its object to provide a practically-constructed and easily-operating cultivator; and it consists in the details of construction substantially as shown on the drawings and hereinafter described and 25 claimed.

In the accompanying drawings, the frame A is composed of tubing *a*, coupled together at their forward ends by elbows *b*, the sides of the frame having connected thereto, by coupling-sections *c*, a transverse brace-rod, *d*, to 30 which is connected the tongue of the cultivator, as shown at B. This tongue in the present instance is formed of the two sections *e* *f*; but, if preferred, a single section may be used.

35 The crank-axes C at their upper ends are connected to the coupling-sections *c* and extend down and outwardly, and upon their extremities are mounted the wheels D. The upper ends of the axes C are screw-threaded, by 40 means of which they are securely connected to the coupling-sections *c*, as shown in Fig. 3, as are also the ends of the transverse brace *d*. The ends of the tubes *a*, which form the frame of the cultivator, are also screw-threaded to couple with the elbows *b*. The lower end of the 45 crank-axes C have connected to them braces E, the ends of which are widened, as shown at *g*, to form a shoulder or collar for the hub of the wheel, the upper ends of said braces being 50 connected in any suitable manner to the forward end of the frame of the machine.

The cultivator-beams are of the ordinary

shape, and at their front ends are connected together to form a slot, *h*, to receive the draw-bar F. There are shown three beams, G, to 55 each cultivator, their rear ends being curved in the usual manner for attaching thereto the shovels H. In forming the slots *h* the outer ones of the beams G are formed of one piece of metal, and the middle beam disposed between them and fastened in position so that a slot will be left, as above described.

The draw-bars F are curved at their upper ends and bifurcated, as shown at *i*, to receive 60 grooved rollers *k*, which work on guides I, 65 suitably attached to transverse rods *l*, connected to suitable clips projecting from the under side of the frame of the machine, or in any other suitable manner attached thereto, as found preferable. The rods *l* form the inner guide for the rollers *k*, thereby retaining 70 the pulley in position while working laterally on the guides, when the cultivators move laterally in either direction. The draw-bars F have perforations *m* at their lower ends to receive bolts *n*, whereby the cultivator-beams 75 may be raised or lowered to regulate the depth of cultivator, as shown more clearly in Fig. 4, a suitable nut, *o*, engaging with the screw-threaded end of the bolts. The cultivators 80 may also be raised or lowered by means of the double-crank arm K, suitably journaled to the sides of the cultivator-frame, as shown at *p*, and to clips *q* on the rear extremities of the tongue-sections *e* *f*.

85 The double crank arms or levers K are connected to the cultivator by means of standards or links L, said levers being pivoted or loosely connected to the upper ends thereof, the standards being bifurcated to embrace the 90 sides of two of the cultivator-beams. The double-crank levers are bent to form handles, as shown at *r*, which extend upon the outer sides of the cultivator-frame and rearwardly, to be in convenient reach of the driver upon 95 the seat M. The seat M is supported upon a transverse spring, N, which is provided at its extremities with sleeves *s*, which fit over the rear ends of rods O, and are held thereon at one end by means of a key, *t*, and at the other end 100 by means of a latch, *u*.

The spring N, as will be seen by reference to Fig. 5, is made in two sections. The inner ends of each section, a suitable distance

throughout its length, have perforations *v*, through which passes a suitable screw-bolt, *w*, upon the end of which engages a tightening-nut, *w'*, to secure the spring-sections together and also secure the seat thereto. By the above means provision is made for lengthening or shortening the spring to increase or diminish its flexibility. The rods *O*, to which the spring is connected, extend through the tubes *a* of the frame, and are held therein by set-screws *a'*, and are consequently adjustable, to change the position of the seat as circumstances require. By lifting the curved handles *r* of the double-crank levers *K* the crank portion thereof, to which the bifurcated standards *L* are connected, when brought forward beyond a vertical line will fall of its own weight until the standards rest against the transverse brace *d*, which will securely hold the cultivators from off the ground.

One or both of the cultivators may be provided with the usual handle, *P*, and the tubes and couplings forming the frame of the machine render the frame not only strong and durable, but comparatively light.

As will be noticed, the coupling-elbows *b* of the frame *A* are provided with depending lugs *b'* as a means for attaching thereto the extremities of the transverse rod *l*, held thereto by means of nuts *c*, engaging the screw-threaded ends of the rod. The coupling-sections *c* are also provided with like lugs, for connecting thereto the rear one of the rods *l*. The eyes or clip *p*, which form the bearings for the double-crank levers *K*, project from the rear end of the coupling-sections *c*, thereby forming a strong and permanent fixture for the levers.

When the cultivators are moved from right to left, the draw-bar *F* will adjust itself to the line of draft, thereby guiding the cultivators with comparative ease. The spring *N*, upon which the seat *M* is supported, is not only adjustable to increase or diminish its power as a spring, but the two sections when adjusted will raise or lower the seat, to adapt its height to suit different persons.

As previously described, two different means are employed for connecting the sleeves *s* of the spring to the extremities of the rods *O*, viz: a key, *t*, and a latch, *u*, said latch acting as a hinge, so that when the key is removed one end of the spring may be detached, or by disengaging the latch with the rod *O* this end may be removed, while the opposite end is held by means of the key, thereby enabling the driver to get in and out of his seat. The rods *O* are drawn out of the tubes *a* sufficiently so that the driver can balance the tongue, this being an important feature of our invention, as well as other details of construction, hereinbefore described. The bifurcated standards *L* are connected to the beams of the cul-

tivator by means of a strong and substantial bolt, *d'*, thus holding the standards firmly to the beams, and also forming a brace therefor, the two serving to steady the cultivator when in operation.

As will be noticed, two rods *l* are shown, for convenience of using a riding or walking cultivator, the forward one of said rods being used for attachment thereto of a riding-cultivator. One or both of said cultivators may be provided with a stirrup, *R*, to receive the foot of the driver, to move the cultivator to either the right or the left. The walking-cultivator is made by a simple change, the rod *l* being placed in the rear of the riding-cultivator at the proper distance, so as to take the draft and weight of the tongue, in order to balance without the weight of driver, as is more clearly shown in Fig. 2, the same connections being made between the cultivator beam and rod; but the draw-bar *F* is reversed, as shown in dotted lines, Fig. 4. By this change the cultivator is kept in the same line with the riding-cultivator, and the manner of attaching the cultivators prevents their hanging back of the wheels when turning.

One draw-rod *l* will answer for both riding and walking cultivator when either is used separately. The stirrup *R* is detachable, so that it may be removed when the device is used as a walking-cultivator.

Having now fully described our invention, what we claim as new, and desire to secure by Letters Patent, is—

1. In a frame for cultivators, the metal tubes *a*, coupling-elbows *b*, and coupling-sections *c*, having depending lugs, as shown, and the former having eye-clips *p*, in combination with the transverse brace *d*, rods *l*, and the double-crank levers *K*, links *L*, and beams *G*, substantially as and for the purpose specified.

2. The combination, with the extensible rods *O*, of the extensible or adjustable spring seat-support *N*, provided at its extremities with sleeves *s*, and detachably connected to the ends of the rods, substantially as and for the purpose set forth.

3. In a cultivator, the frame *A*, constructed as described, the transverse guides *I*, and rods *l*, in combination with the plow-beams, the crank-levers *K*, for raising and lowering them, and the curved and bifurcated draw-bars *F*, provided with grooved rollers *k*, substantially as and for the purpose set forth.

In testimony that we claim the above we have hereunto subscribed our names in the presence of two witnesses.

DENNIS S. BLUE.
LEANDER HALTER.
